FINNED TUBE

Clyde S. Simpelaar, Racine, Wis., assignor to
Modine Manufacturing Company, Racine, Wis.,
a corporation of Wisconsin

Application August 8, 1946, Serial No. 689,092

9 Claims. (Cl. 257—262.14)

1

This invention relates to tubular finned heat exchange elements, and its principal object is to provide a fluid conducting tube with integrally formed fins, either projecting inwardly from its tube wall or projecting outwardly therefrom, or projecting both inwardly and outwardly from its wall.

Various means have heretofore been used to provide tubes with finned surfaces. The principal objection to previously made finned tubes is the cost of the basic tube on which fins of separate material are added, or expensive tubes, which are further formed or worked to provide extended surfaces.

Another object is to provide a finned tube composed of a metal strip wound helically upon itself into a tubular form, and having fins struck up therefrom along the length of the portion thereof which is disposed at least on one side of its median line, and having an imperforate overlapping portion covering the perforations left by the struck up fins, and the contacting faces of the convolutions being brazed, soldered or otherwise bonded together to provide an imperforate tube having fins projecting from its inner or outer face, or from both faces.

Tubes embodying the present invention are applicable to practically any type of heat exchangers. The tubes represent in themselves a combination of tube, inside fins, outside fins and headers, when the ends thereof are of a form having hexagonal or other polygonal shaped ends which, when nested, and joined by a welding or brazing process, may constitute a complete core assembly.

Particular applications of the present tube would be for heat exchangers when heat transfer coefficient of fluid inside of the tube or tubes is controlling, and a substantial increase in the overall heat transfer coefficient can be obtained by increasing the surface and fluid turbulence on the side which is controlling. Other specific types of applications would be hot gas flues in boilers and hot water heaters, jacketed exhaust stacks for heat recovery, etc., counter flow gas to gas heat exchangers.

With these and other objects and advantages in view, this invention consists in the several novel features hereinafter fully set forth, and more particularly defined in the appended claims.

The invention is clearly illustrated in the drawings accompanying this specification; in which

Fig. 1 is a side elevation of a partially formed tube embodying one form of the present invention;

Fig. 2 is an end elevation thereof, looking in the direction of the arrow 2 in Fig. 1;

Fig. 3 is a cross-section taken on the line 3—3 of Fig. 1;

Fig. 4 is a fragmentary horizontal section through the wall of the tube taken on the line 4—4 of Fig. 1;

Fig. 5 is a similar section of a slightly modified form of the invention;

Fig. 6 is a similar section of a second modification;

Fig. 7 is an elevation of a number of the tubes seen in Fig. 1, nested and bonded together to form a radiator core;

Fig. 8 is a fragmental perspective view of a tube strip illustrating one form of fin;

Fig. 9 is a fragmental perspective view illustrating another form of fin;

Fig. 10 is a fragmental perspective view of still another form of fin;

Fig. 11 is a side elevation of a partially completed tube embodying another modified form of the invention;

Fig. 12 is a cross-section taken on the line 12—12 of Fig. 11;

Fig. 13 is a side elevation of a partially completed tube illustrating another modified form of the invention;

Fig. 14 is an end view of the tube seen in Fig. 13, looking in the direction of the arrow 14 in Fig. 13;

Fig. 15 is a detail horizontal section through the wall of the tube seen in Fig. 13, taken on the line 15—15 of Fig. 13;

Fig. 16 is a side elevation of a partially formed tube embodying still another modified form of the invention;

Fig. 17 is a front elevation of an automobile radiator, of which the core is composed of tubes embodying the form of tube illustrated in Figs. 1 and 7;

Fig. 18 is a detail horizontal fragmental section taken on the line 18—18 of Fig. 17, with one of the tubes partially broken out and others shown partially in dotted lines;

Fig. 19 is an end elevation of a group of finned tubes embodying the present invention, and provided with external extended finned surfaces; and

Fig. 20 is a side elevational view of the structure illustrated in Fig. 19.

Referring to said drawings, and first to Figs. 1 to 4 inclusive, the tube shown therein is formed of a metal strip 20 wound helically upon itself 55 to form a tube 21. The metal strip is struck up

with suitable dies to form fins 22 that occupy substantially one-half of the width of the metal strip. These fins may take any of several forms, and the metal strip may be wound upon itself to bring the fins on the internal side of the tube, or the metal strip may be wound so as to bring the fins on the external side of the tube wall, as is seen in Figs. 11 and 12.

The fins may be omitted from the end portions of the strip and the end portions of the tube may be expanded outwardly to provide walls 23 of many sided configurations such, for instance, as hexagonal or other polygonal configurations, whereby the tubes may be assembled, as seen in Fig. 7, with the flat faces of each tube contacting with other flat faces of other tubes, and bonded together to form the core of a radiator, as is well understood.

In winding the strip upon itself, the imperforate part thereof may overlie the finned perforated part of the next adjacent convolution, thereby causing the apertures which are formed as a result of striking up the fins from the metal strip to be covered. The metal strip may comprise a strip straight in cross-section, as shown in Fig. 4, and a plain lap joint may be made between contiguous convolutions. However, the metal strip 20^a may be preformed by offsetting the strip longitudinally thereof midway between its side edges, as is seen in Fig. 5. When the preformed strip, as shown in Fig. 5 is used, a cylindrical tube results therefrom. In either case, it is to be understood that the overlapping contiguous convolutions of the tubes are brazed, soldered or otherwise bonded together.

In Fig. 6 is shown a slight modification of the present invention. In this form of tube, the metal finned strip 24 is wound helically and the convolutions are butt joined. This metal strip is formed with the fins 25 as in other forms. A second strip 26 is wound helically upon itself in contact with the strip 24 and is bonded thereto. The strip 26 is imperforate and serves to close the apertures formed in the finned strip.

Fig. 8 shows a fragment of a metal strip 20, struck up with suitable dies to form square or rectangular fins 22^a; Fig. 9 illustrates a metal strip 20 struck up with suitable dies to form a fin 22^b of triangular form, and Fig. 10 illustrates a metal strip 20 struck up with suitable dies to form a semi-circle fin 22^c. Obviously, the fins may be given any desirable shape best suited for the particular purpose intended, and may be formed by scarfing the strip without piercing the strip.

Figs. 11 and 12 illustrate a modified form of the invention, wherein the fins 22^d are disposed on the external side of the tube. The fins are struck up along the strip at one side of its median line as before, but the metal strip is wound on itself to leave the fins disposed on the external side of the wall formed by the wound strip, the apertures left by the fins being covered by the imperforate part of the strip by the next adjacent convolution, which in this case is on the inner side of the tube wall.

In the modified form of the invention, illustrated in Figs. 13 and 14, fins 22^e are disposed on the inner face of the tube wall, and other fins 22^f are disposed on the outer face of the tube wall. In this case, the metal strip 20^b is struck up with suitable dies to form rows of fins 22^e at one side of the median line of the strip, that extend in one direction from the strip, and other rows of fins 22^f are struck up at the other side of the me-

dian line of the strip and extend in the opposite direction from the strip. Between the two rows of fins, the strip is left imperforate. This metal strip is wound upon itself so that the imperforate part of the strip covers the apertures left by the fins along the inside of the tube wall, and also covers the apertures left by the fins on the outside of the tube wall, so that all of the apertures are covered by the imperforate part of the strip (see Fig. 15).

From the above it is clear that the double walled imperforate tube is formed having inwardly and outwardly projecting fins extending from the wall thereof.

Obviously, the fins can be struck up from the metal strip to stand in planes parallel with the axis of the tubes, or they may stand at right angles thereto, or at any other suitable angle to the axis of the plane.

In the previously described form of the fins, the metal strip is wound externally of the tube. Fig. 16 shows a modification of the invention in which the metal strip 20ⁱ is wound internally of the tube. The metal strip may be offset as in the form of a metal strip illustrated in Fig. 5, and the fins 22^g project inwardly from the tube wall formed by the helically wound strip.

Fig. 17 illustrates an application of a finned tube to the core of an automobile radiator 27. Finned tubes having hexagonal ends 23 are nested together with the flat faces of the end portions bonded together, and the endmost tubes bonded to the walls 28 of the radiator structure.

In Figs. 19 and 20 several of the finned tubes are illustrated, to which is applied extended fin members 29 of common construction bonded to the finned tubes. This arrangement provides a core for many types of heat exchangers.

In each form of the invention above described, the metal strip may be pre-formed and wound upon itself by automatic machinery, which forms no part of this invention, and the bonding may take place as the strip is being wound. Since the tube, when fabricated becomes a solid tube; that is, there are no perforations not covered by solid metal, it may be cut at any point. As a convenience, the strip may be wound into a tube of indefinite length, and may be subsequently cut up into desired lengths. The ends 50 may be left square, as shown in Figs. 13 and 16, and bonded to suitable headers, or they may be expanded into hexagonal or other polygonal forms as required.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A finned tube, comprising a wound metal strip having helical overlapping bonded together convolutions, said strip having an imperforate section extending along its length at one side of its median line, the section of the strip on the other side of the median line having fins struck up therefrom inwardly of the edges of the strip, which leave apertures in the strip initially occupied by said fins and the imperforate section of the strip covering said apertures.

2. A finned tube, comprising a wound metal strip having a longitudinally extending, lateral

5 offset, one offset section being imperforate, and the other offset section having fins struck up therefrom, which leave apertures initially occupied by the fins, said strip having helical bonded together overlapping convolutions, with the imperforate offset sections overlapping the oppositely offset apertured sections and closing the perforations thereof.

3. A finned tube, comprising a wound metal strip having helical overlapping bonded together convolutions, said strip having an imperforate section extending along its length midway between its side edges, the sections of the strip adjacent its edges having reversely struck up fins, which leave apertures in the strip initially occupied by said fins and the imperforate sections of the strip covering said apertures.

4. A finned metal tube formed from strip material comprising helically wound and bonded together convolutions overlapp'g one another to provide a tube of substantially double thickness, a plurality of fins struck from portions of the material forming one of the plies of the tube wall, and leaving openings in such ply initially occupied by said fins, the material forming the other ply covering said openings.

5. A finned tube comprising a metal strip having a longitudinally extending imperforate section, portions of the said strip laterally adjacent to said section having fins struck up therefrom and extending transversely thereto, which leave openings in the strip initially occupied by said fins, said strip having helically wound, overlapping, bonded together convolutions, with the imperforate section of the strip covering said openings.

6. A finned tube comprising a metal strip having a longitudinally extending, imperforate section, portions of the said strip laterally adjacent to said section having fins struck up therefrom and extending inwardly transversely thereto, the planes of the respective fins extending transversely to the edges of said strip, said fins leaving openings in the strip initially occupied by such fins, said strip having helically wound, overlapping, bonded together convolutions, with the imperforate section of the strip covering said openings.

7. Finned tubing comprising a longitudinally extended strip of metal having fins along one longitudinal edge portion of the same partially severed and bent out of the plane of the strip and leaving openings along said edge portion of the strip, the opposite edge portion of the strip

being imperforate and of a transverse extent at least equal to the transverse extent along the first mentioned edge made perforate by the partial severance of the fins, said strip being rolled with the imperforate edge portion of the same covering the openings in the opposite fin carrying portion of the same.

8. A finned tube comprising a metal strip having a longitudinally extending, imperforate section, portions of the said strip laterally adjacent to said section having fins struck up therefrom and extending outwardly transversely thereto, the planes of the respective fins extending transversely to the edges of said strip, said fins leaving openings in the strip initially occupied by such fins, said strip having helically wound, overlapping, bonded together convolutions, with the imperforate section of the strip covering said openings.

9. Externally and internally finned tubing comprising a longitudinally extending strip of metal having fins along both longitudinal edge portions of the same partially severed and bent out of the plane of the strip, and leaving openings along said edge portions of the strip, the fins along one edge portion being disposed on one side of the strip, and the fins along the other side of the strip being disposed on the opposite side of the strip, the intermediate portion of the strip being imperforate and of a transverse extent at least equal to the transverse extent along both edges made perforate by the partial severance of the fins, said strip being rolled, with the imperforate, intermediate portion of the strip covering the openings in the fin carrying portions of the same.

CLYDE SIMPELAAR.
